APPARATUS FOR CORRECTIVE DRAFTING OF STRANDS OF DISCONTINUOUS FIBERS

Malcolm A. Sanborn, Kingston, N.Y., and William G. Klein, Newton, Mass., assignors to Bates Manufacturing Company, a corporation of Maine

Application October 28, 1955, Serial No. 543,397

10 Claims. (Cl. 19—70)

This invention relates to a system for continuously drafting strands composed of discontinuous fibers by attenuation between two or more sets of draft rolls driven at different speeds, and more particularly to a system of that general organization wherein the relative speeds are induced by variable drive components controlled by sensing elements actuated by the mass or bulk of the original strand.

In the production of yarn from staple fibers according to conventional methods there is formed, after initial dispersion by openers and cards, an essentially continuous strand, usually called a "sliver," composed of a plurality of overlapping fibers loosely but effectively held together by inter-fiber friction and entanglement. Since, in most cases, the weight of this initial sliver is greater than the desired weight of the final yarn, it is subjected to subsequent attenuating processes, as by drafting. In most staple yarn production, the drafting serves a second function of increasing the straightness and parallelism of the fibers along the strand axis.

It is common to most textile systems that the average weight of the initial slivers varies from one production unit to another. These slivers are also variable in weight distribution along their length. Accordingly, reduction through standard draft settings will not consistently give the desired yarn weight. Some reduction of the gross and variable deviation from the desired weight is accomplished by combining a plurality of these initial slivers to average out these inequalities prior to reduction to desired final weight. This combining process, known in the art as "doubling," is only partially successful in attaining this objective; it may, in fact, lessen the normality of the total product by adding the characteristics of a highly abnormal sliver to other slivers which might initially have been quite regular and normal.

This process of doubling to average out strand abnormalities has a basic disadvantage because the resulting heavier strand must receive proportionally more reduction by drafting to attain the desired final yarn weight. This adds both equipment and operating expense. Most important to the significance of our invention, the increased necessary drafting results in increased within-strand variability of a short-term nature. It is well known in the textile arts that, during drafting by conventional means, there are erratic fiber movements and also fairly regular drafting waves which increase the variability of the drafted strand compared to the original strand. Various combinations of doubling and re-drafting are resorted to according to the relative importance in the final product of long-term compared to short-term variations. At best, however, the resulting product is a compromise as to uniformity, the system itself being self limiting.

It is logical and obvious that a corrective device acting on the initial or intermediate strands would obviate much of the objectionable result of doubling and re-drafting. Various attempts have been made in the past to devise such corrective mechanisms. However, these prior at-

2

tempts, although theoretically feasible, have been commercially unsuccessful.

It has been observed that two essential elements must be present to effect significant and worthwhile corrective action on a non-uniform strand by varying the relative speed of two pairs of drafting rolls. Within the general concept of controlled variable drafting, such that the heavier-than-desired sections are attenuated to a greater extent and the lighter to a lesser extent, it has been found that a variable speed driving system for the drafting rolls capable of responding very quickly and sensitively to changes in the measurement signal is essential to achieve worthwhile gains in uniformity at reasonable operating speeds. Further, it has been found that within low-inertia systems which satisfy this requirement, it is particularly important to provide means to compensate for incidental variation in drafting resistance to insure the precise drafting speed momentarily indicated for a specific degree of correction. The prior art systems either lack these elements or have attempted to introduce them by means inherently incapable of meeting the required exacting conditions.

As an example of a low-inertia variable drive, the present invention preferably utilizes an electromagnetic slip clutch, the torque output of which is governed by a control circuit. For significant reasons, a speed control circuit of the "feed-back" or closed loop type has been employed, having found that the common calibrated or open loop principle is not sufficiently sensitive or precise for the critical requirements of the problem. An open loop speed control system, such as, for example, a system employing a strand measuring device which alone controls the speed of a variable drive element, would be appropriate and satisfactory only if the variable drive element where both of low inertia and of such power as to practically completely over-ride or negate the effect of variations in drafting resistance. These two requirements are essentially in conflict, and from a practical standpoint are not attainable without feed-back with known equipment in a satisfactory compromise appropriate to the problem of corrective drafting of typical textile slivers or strands at economic speeds. Thus, prior art has been limited by dependence on purely calibrated control systems.

According to the present invention, a feedback voltage is generated which is directly responsive to the actual relative speed of the drafting rolls, and the feed-back is utilized to modify the control signal for discrepancies due to drafting resistance and possible changes in characteristics of the driving mechanism. As is later described, this also accelerates the response. The essence of this invention is the novel and uniquely appropriate application of a feed-back control system to the important and heretofore unsolved problem of correcting weight variations in textile strands by drafting an amount proportional to the mass or bulk.

For a complete understanding of the present invention, reference may be had to the detailed description which follows and to the accompanying drawings in which:

Fig. 1 is a schematic box-type diagram of one form of the control system of the present invention; and

Fig. 2 is a schematic perspective view of the elements comprising a particular embodiment of the present invention.

The present invention may be described in a general manner by reference to the box-type diagram represented in Fig. 1 of the drawings. According to that figure, the mass of a moving sliver is measured by a sensing means 1 which detects variations in the uniformity of the mass of the sliver, and these variations are converted by a transducer element 2 into a signal voltage which may,

if necessary, be amplified by a conventional unit 3 before being fed into a summation point 7 of a variable drafting system, denoted generally by the reference numeral 4.

The variable drafting system 4 includes a forward circuit 5 and a feed-back circuit 6. A D.C. voltage is generated in the feed-back circuit by a tachometer generator 40, which voltage is proportional to the relative speed of the drafting rolls 10, 11 (see Fig. 2). The feed-back voltage is calibrated by the speed adjusting control 42 and converted from D.C. to A.C. by a converter 38 before being introduced to the summation point 7, at which point the feed-back voltage is subtracted from the mass signal voltage to produce an "error" voltage. The "error" voltage is amplified by a phase sensitive amplifier 44 and rectified by a rectifier 8, and the "error" voltage is used to control the rotational torque applied to the draft rolls 11. For example, the "error" voltage may control the slip of a clutch 15, thereby, in turn, regulating the speed of the feed rolls. In this manner, the actual relative speed of the feed rolls is controlled by both the mass voltage and the speed voltage, so that changes in mass or small deviations in speed of the draft rolls produce substantial changes in "error" voltage to bring this roll speed to that dictated by the mass at any instant. Because of this action the system is capable of precise control of speed and fast response to changes in mass.

Referring to Fig. 2 which illustrates a specific embodiment of the present invention, the non-uniform strand or sliver A which is to be processed to improve its uniformity is passed through two sets of rolls 10 and 11 suitably spaced apart and separately driven to permit attenuation of the strand A therebetween. Although the invention as described employs only two sets of rolls, any number may be provided with the relative speeds of successive pairs being regulated, if desired.

The shafts of the upper and lower rolls of the set 10 carry meshing gears 10a, 10b, and the rolls 10 are driven at uniform speed by a motor 12. The shafts of the upper and lower rolls of the set 11 also carry meshing gears 11a and 11b, and the rolls 11 are adapted to be driven from a constant speed motor 13 through a transmission which includes transmission means, such as a belt drive 14, a magnetic slip clutch 15, and a shaft 16 connecting the driven element of the slip clutch with the rolls 11. To provide a desired damping effect, the shaft 16 is coupled to a "viscous" load, such as a shorted generator 17. Alternatively, this may be accomplished electrically by a suitable kinetic damping or by an "anti-hunt" circuit. Obviously, the draft rolls 10, 11 may be driven by a single motor.

The speed of the rolls 11 is varied by controlling the slip of the magnetic clutch 15. It is evident that if the peripheral linear velocity of the rolls 11 is greater than that of the rolls 10, the portion of the strand A between the two sets of rolls will be subjected to tension which will have a drawing effect on that portion of the strand A. By increasing this drawing effect on heavier portions of the strand and by diminishing this drawing effect on lighter portions of the strand, it is possible to produce a strand of relatively uniform mass.

The detecting or sensing unit, in one preferred form, includes a guide block 20 having an open channel or slot 21 formed therein and a sensing element comprising a weighted movable tongue 22 accommodated within the channel or slot 21 and a pivotal lever 23 supporting the tongue 22 at the free end thereof. The fixed end of the lever is suitably supported on a pin 24 in a suitable base or platform B.

The side walls 21a and the base 21b of the channel 21 curve or taper outwardly at the entrance end, and the lower edge of the tongue 22 is curved or rounded in the direction of the moving strand to guide the strand through the channel.

As the strand or sliver A is advanced through the grooved channel or slot 21 by the action of the rolls 10, the weight of the tongue 22 accommodated within the groove 21 compresses the strand to a substantially uniform density in order to make possible an accurate measure of the sliver mass. The tongue 22 will, of course, move in a vertical direction in response to and simultaneously with the changes in the mass of the fiber bundle or strand passing beneath it, and this vertical movement is an accurate measure of the mass of this portion of the strand.

The pivotal movement of the lever 23 in response to variations in the mass of the strand displaces the movable core 30a of a conventional linear variable differential transformer 30. The transformer 30 comprises the movable core 30a, a primary winding 30b and secondary windings 30c. The core 30a is provided with an upwardly projecting extension 31 which carries a screw or collar 32 and a compression spring 33. The compression spring acting against a fixed surface of the transformer engages the collar 32 and urges the upper end of the extension 31 in contact with the lower end of an adjustable set screw 34. In this way, any movement of the pivotal lever will shift the position of the core 30a of the transformer. Thus, when a constant A.C. voltage is impressed across the input terminals 36 of the transformer, the voltage at the output will be determined by the relative position of the core, which position, in turn, is determined by the thickness of the compressed strand measured by the sensing element.

The output voltage of the transformer 30 may be amplified by conventional means represented by the reference numeral 37, and the amplified voltage is then applied to the input of a phase sensitive amplifier 44 in opposition to the adjusted A.C. voltage generated by a tachometer generator 40.

The tachometer generator 40 is driven by a suitable drive transmission 41 from the shaft 16. The voltage output of the generator 40, therefore, is proportional to the speed of operation of the rolls 11. The D.C. voltage generated by the tachometer 40 is converted to A.C. by conventional means 38 and then impressed upon the input of the phase sensitive amplifier 44 in bucking fashion to the amplified A.C. output voltage of the transformer 30. The feed-back voltage will equal the mass voltage only when the output speed is that required to maintain the proper output mass. When these two desired voltages are not equal, a differential, or error, voltage is amplified by the phase sensitive amplifier 44, rectified to D.C. by the rectifier 8, and then impressed across a magnetic coil 15a of the magnetic clutch. The slippage of the clutch 15 and, therefore, the speed of the rolls 11 is determined by the "error" voltage impressed across the coil 15a.

If, therefore, the mass of the strand measured by the sensing element is greater or less than the expected norm, the slippage of the magnetic clutch will be altered, resulting in a change in the relative speed of the rolls 10, 11.

Various other means may be employed to drive the draft rolls 11, such as a variable speed motor in combination with an amplitidyne. The magnetic slip clutch 15, however, is preferred. The principal advantage of the magnetic slip clutch over a variable speed motor is that the power required to control clutch slippage is a small fraction of that needed to drive and accelerate a motor capable of performance equal to that of a clutch. The reduced power requirement permits simpler equipment to be used for the amplifier. In order to be applicable to this problem, a magnetic slip clutch must be smooth in its action and be capable of running in continuous slip with infrequent maintenance. Any electro-magnetically activated clutch which fulfills these requirements can be used, and the term magnetic slip clutch is used here to indicate any clutch of this general type. One such clutch is the magnetic fluid clutch recently

developed by the National Bureau of Standards and described in the NBS Technical News Bulletin, 37, 54-60 (1948) and 34, 169-174 (1950). The driving and driven members of the clutch are immersed in a magnetic fluid, iron particles suspended in oil. When a magnetic field is applied to the fluid by means of a coil carrying electrical current, the fluid tends to coalesce so that a torque has to be applied to the output shaft to make the clutch slip when the input shaft is being driven by external means. This slip torque is substantially proportional to the current flowing in and, therefore, to the voltage applied to the coil. The torque-voltage characteristic changes somewhat with time, but this fact does not affect its performance in this application because it is connected in a feed-back control system which compensates for such changes.

Since the drafting resistance or working load on the draft components, at least with many common types of textile fibers, is not proportional to the speed of drafting, a variable torque drive will not produce proportionally variable speeds with adequate stability. Thus, the "viscous" load element 17 coupled to the variable speed element has been found desirable to change the torque-to-speed relationship by imposing a resistance which increases with increased speed. The degree of "viscous" damping is designed or adjusted so that the torque-to-speed relationship is reasonably constant, the feed-back circuit making the final minor adjustment to the precise speed indicated for appropriate corrective drafting. As an example of a "viscous" load element, we have found that a shorted D.C. generator is suitable and has an advantage in that the amount of loading can be easily adjusted by varying the field excitation. A rotating stirrer in an oil bath is another example. The tachometer-generator itself might be of a type to provide a proper "viscous" loading.

The element 42 comprises two speed adjusting controls which assure that the sliver will be attenuated to the proper level and that a given change in mass will cause the proper change in speed. This latter effect is called tracking. The tracking control is a voltage divider which takes a suitable fraction of the D.C. tachometer generator voltage for use in the control so that a given change in speed will produce the proper change in feed-back voltage. The other control is achieved through the application of a bias voltage which sets the average speed level.

Synchronization of the specific corrective drafting speed with the mass earlier measured can be effected by adjusting speed of throughput to match any delay in the response of the system, by spacing of the measuring element in relation to the drafting zone, by a delay device in the sensing signal system, or by any combination of the three.

The D.C. to A.C. converter 38 comprises an electronic tube arranged in a conventional circuit to produce an A.C. voltage of a magnitude proportional to the adjusted D.C. tachometer generator voltage, and of the same frequency and opposite phase as the amplified A.C. output voltage of the transformer 30.

The amplified output voltage of the transformer 30, referred to as the mass voltage, and the calibrated speed voltage generated by the generator 40, referred to as the speed voltage, are applied to the phase sensitive amplifier 44 in "bucking" manner, so that the actual input to be amplified is the difference of the two. The difference or "error" voltage is in phase with either the mass voltage or the speed voltage, whichever is larger.

The phase sensitive amplifier 44 is of conventional design. With the "error" voltage equal to zero there is still a D.C. output voltage called the zero signal output. This D.C. voltage causes a certain voltage to be applied to the clutch, called the null voltage. When the mass voltage dominates the speed voltage, the D.C. clutch voltage, and thus the speed, is increased; and, when the speed

voltage dominates, the D.C. clutch voltage and speed are decreased.

There are, of course, alternative arrangements which may be used within the limits of the invention described in the claims. The rolls 10 rather than the rolls 11 may be driven at variable speed. Two or more sets of rolls may be used and more than one set can be driven at variable speeds. It may be desirable, in order to guard against making a product of improper mass when the prime mover's speed varies, to use two tachometers, utilizing the difference of the two voltages for control purposes.

Any mass measuring device which reliably produces a signal proportional to mass may be used. Capacitances and photoelectric devices, such as those used on textile fiber uniformity measuring devices, are alternatives which may be used in place of the tongue and groove device shown in Fig. 2. As a further modification, we have achieved satisfactory results using a D.C. amplifier as well as with an A.C. amplifier in place of the phase sensitive amplifier now employed. As discussed before, any form of "viscous" load which is adequate may be used, and, under certain circumstances, no "viscous" load may be necessary. It may be omitted without altering the essential principles of the invention.

While we have shown specific systems, by way of example, it is understood that the invention is not to be limited to any specified form or embodiment except insofar as such limitations are set forth in the claims which follow.

We claim:

1. Apparatus for corrective drafting of strands made from discontinuous fibers comprising pairs of draft rolls, the strand travelling from one pair to the next, means for measuring the mass of the strand comprising a restricted passage through which the strand is guided, weighted means movable within said restricted passage for compressing the strand to substantially a uniform density, a variable speed drive for at least one of the pairs of draft rolls, means controlled by the movement of the weighted means for regulating the speed of the drive, means for generating a voltage the value of which is a function of the relative speed of the two pairs of rolls, and means for impressing said generated voltage as a feed-back control for said variable speed drive to further insure the operation of the variable speed drive system at the speed dictated by the mass measurement, thereby drafting the strand between the pairs of draft rolls the amount indicated by the measured mass to produce a strand of improved uniformity.

2. Apparatus for corrective drafting of strands made from discontinuous fibers comprising means for detecting the uniformity of a moving fiber strand, first and second sets of draft rolls, the strand travelling from one set of draft rolls to the other in succession, means for driving at least one of said sets of draft rolls through a drive transmission which includes a magnetically controlled slip clutch, the slip of said clutch determining the relative velocity of the two sets of rolls, thereby controlling the degree of attenuation of the strand between the two sets of draft rolls, an electrical circuit for controlling the slippage of the clutch, a generator driven at a speed which varies as the relative speed of the draft rolls, the generated voltage being impressed upon said electrical circuit, and transducer means controlled by the detecting means for producing a variable voltage determined by the mass of the strand sensed by the detecting means, said voltage being impressed on the electrical circuit opposing said generated voltage, the resulting flow of current in said electrical circuit determining the relative velocity of said sets of rolls.

3. Apparatus for corrective drafting of strands made from discontinuous fibers comprising first and second sets of draft rolls, the strand travelling from one set of draft rolls to the other in succession, means for driving

one of said sets of rolls at a constant speed, means for driving the other of said sets of rolls through a drive transmission which includes a magnetically operated slip clutch, the degree of slip of said clutch determining the speed of the rolls driven thereby, a channel forming a narrow passageway through which the strand is fed in an axial direction, a pivoted lever, a weighted tongue carried by said pivoted lever, said tongue engaging the moving strand within the channel and compressing it to a relatively uniform density, the pivotal movements of the lever being a measure of the variations in the uniformity of the strand, a transducer having a movable core, the position of the core of said transducer being determined by the pivotal movements of said lever, and an electrical circuit to transmit the variations in the output voltage of the transducer to the magnetically controlled slip clutch to alter the speed of the rolls driven thereby in accordance with the degree of attenuation desired on the portion of the strand between the two sets of rolls.

4. Apparatus as set forth in claim 3 including a generator driven by the variable speed rolls, the output voltage of said generator being proportional to the relative speed of the draft rolls and being impressed on said electrical circuit in bucking fashion to the output voltage of the transducer, the summation of the two voltages serving to control the magnetically controlled slip clutch.

5. Apparatus for corrective drafting of strands made from discontinuous fibers comprising means for detecting the uniformity of a moving fiber strand, first and second sets of draft rolls, the strand travelling from one set of draft rolls to the other in succession, means for driving at least one of said sets of draft rolls through a drive transmission which includes a magnetically controlled slip clutch, the slip of said clutch determining the relative velocity of the two sets of rolls, thereby controlling the degree of attenuation of the strand between the two sets of draft rolls, an electrical circuit for controlling the slippage of the clutch, a generator driven at a speed which varies as the relative speed of the draft rolls, the generated voltage being impressed upon said electrical circuit, transducer means controlled by the detecting means for producing a variable voltage determined by the mass of the strand sensed by the detecting means, said voltage being impressed on the electrical circuit opposing said generated voltage, and voltage control means for regulating at least one of the voltages impressed on said electrical circuit, providing a predetermined relationship between the relative speeds of the draft rolls and the mass of the portion of the strand being attenuated, the flow of current in said electrical circuit resulting from deviation from this predetermined relationship, said current causing the relative speed of the draft rolls to change and establish the said relationship.

6. Apparatus for corrective drafting of strands made from discontinuous fibers comprising at least two sets of draft rolls, the strand traveling from one set to the next for attenuation therebetween, a variable speed drive for at least one of the sets of draft rolls, a signal summing circuit, the output of which regulates the variable speed drive, means for measuring the mass of the strand, means for converting the measurement of the mass of the strand into an electrical input impressed on said signal summing circuit, means for generating a voltage the value of which is determined by the actual relative speed of the sets of draft rolls, and means for impressing said voltage on said signal summing circuit.

7. Apparatus for corrective drafting of strands made from discontinuous fibers comprising at least two sets of draft rolls, the strand traveling from one set to the next for attenuation therebetween, a variable speed drive for at least one of the sets of draft rolls, an electrical circuit for regulating the variable speed drive, means for measuring the mass of the strand, means for converting the measurement of the mass of the strand into a voltage input impressed on said electrical circuit, means for gen-

erating a voltage, the value of which is determined by the actual relative speed of the sets of draft rolls, and means for impressing the generated voltage on said electrical circuit to compensate for any discrepancy between the relative speed of the draft rolls necessary to afford the desired attenuation and the actual relative speed of the draft rolls, the said electrical circuit serving as a summing circuit for the different voltages impressed thereon.

8. Apparatus for corrective drafting of strands made from discontinuous fibers comprising at least two pairs of draft rolls, the strand travelling from one pair to the other in succession, means for measuring the mass of the strand, a variable speed drive for at least one of the pairs of draft rolls, means controlled by the means for measuring the mass of the strand for regulating the speed of the drive, means for generating a voltage the value of which is a function of the relative speed of the two pairs of rolls, and means for impressing the generated voltage as a feed-back control on said variable speed drive to insure the operation of the variable speed drive at the speed dictated by the mass measurement, thereby drafting the strand between the pairs of draft rolls by the amount indicated by the measured mass to produce a strand of improved uniformity.

9. Apparatus for corrective drafting of strands made from discontinuous fibers comprising first and second sets of draft rolls, the strand travelling from one set of draft rolls to the other in succession, drive means for said first and second sets of draft rolls, a magnetically controlled slip clutch for transmitting the drive to at least one of said sets of rolls, the degree of slip of the clutch determining the relative speed of rotation of the two sets of rolls, an electrical circuit for impressing a predetermined voltage on said magnetically controlled slip clutch to control the degree of slip thereof, the torque transmitted by the clutch varying directly with the voltage impressed thereon, means to detect variations in the uniformity of the strand, transducer means for translating the variations in uniformity into variations in the voltage impressed on the magnetically controlled clutch, means for generating a voltage the value of which is a function of the relative speed of the two sets of rolls, and means for impressing the generated voltage as a feedback control on said magnetically controlled slip clutch to insure the operation of the magnetically controlled slip clutch at the speed dictated by the variation in uniformity, thereby drafting the strand between the sets of draft rolls by the amount indicated by the means to detect variations in the uniformity of the strand to produce a strand of improved uniformity.

10. Apparatus for corrective drafting of strands made from discontinuous fibers comprising at least two pairs of draft rolls, the strand traveling from one pair of draft rolls to the other in succession, detecting means to measure variations in the uniformity of the strand, a variable speed drive for at least one of the pairs of draft rolls, means controlled by the detecting means for regulating the variable speed drive to change the relative speeds of rotation of the two pairs of draft rolls, means for generating a voltage the value of which is a function of the relative speeds of rotation of the two pairs of draft rolls, and means for impressing the generated voltage as a feed-back control on said means controlled by the detecting means to insure the operation of the variable speed drive at the speed dictated by the detecting means, thereby drafting the strand between the pairs of draft rolls by the amount indicated by the detecting means to produce a strand of improved uniformity.
